MEDICAMENT VEHICLES OR EMULSIONS

Morton B. Crowe, Tulsa, Okla., assignor to Crowe Chemical Company, Tulsa, Okla., a corporation of Oklahoma

No Drawing. Application January 15, 1945,
Serial No. 572,965

6 Claims. (Cl. 167—58)

This invention relates to a medicament vehicle; and has special reference to a liquid vehicle that is, and that possesses all of the attributes and characteristics of, a true water-phase emulsion, and which functions to suspend indefinitely or permanently different respective medicative substances.

A general object of the invention is to provide a medicament vehicle in the form of a true water-phase emulsion that remains constant and unvaried in quality for indefinitely long periods of time during varying temperatures; that will not deteriorate nor become rancid as a result of ageing, but will remain stable and applicable to its intended beneficial medicative uses when properly packaged and sealed; which may be diluted with additional distilled water or normal saline solution when said additional dilution is desired, or is needed in order to modify the relative proportions of the medicaments to the entire preparation; and which will function as a vehicle for the suspension of both soluble and solid medicaments to be applied and spread topically. The vehicle of the present invention, which attains this objective, is and possesses the indispensable characteristics and qualities of a true water-phase emulsion; is freely dispersible in watery exudates or serous discharges of the body; is wholly without greasy feel or appearance; is free from saponified fatty acids; is easily applied and easily removed, and does not soil clothing; has and shows Brownian movements when examined under a microscope of high power; is capable of wetting either a watery or oily surface; and has detergent and foaming properties.

Specific objects of the invention are to provide an improved water-phase emulsion for topical application which may be diluted with sterile water or normal saline solution to a desired consistency, and is inhibitory to certain bacteria, for example, *Staphylococcus aureus*; and to provide an improved emulsion having detergent properties, and is applicable to the following beneficial uses: For softening adherent dressings on burns, skin grafts, and other wounds, in order that said dressings may be easily and painlessly removed without interference to or with granulation tissue; for debriding wounds and adjacent areas without trauma; for use in the treatment of wounds wherever it is impossible or difficult to secure bandages; for saturating gauze to be used as non-drying drainage packs for post-operative treatment of nasal, mastoidal, and other surgical wounds; for the treatment of burns even to the third degree; and for the treatment of cer-

tain affections due to allergenic conditions. Due to osmosis or osmotic pressure, a certain amount of this medicament vehicle or true water-phase emulsion is believed to penetrate the skin in an unchanged condition, and it has been used with highly satisfactory results in cases which did not react to the beneficial extent desired to other known treatments.

Other specific objects of the invention are to provide an improved water-phase emulsion functioning as a medicament vehicle for the permanent suspension of particles of solid medicaments reduced to such a degree of fineness by proper milling action that said particles remain in suspension permanently, providing a medicated vehicle having the appearance of a smear even when examined through a microscope of high power such, for instance, as 1000 power. Such a medicated vehicle, does not interfere with the therapeutic action of the medicament; does not wall off the medicament from the affected area as do many or all semi-solid grease vehicles, or those containing saponified fatty acids, waxy products, or gums; is compatible with most of the medicaments of the physicians' choice; suspends the medicament uniformly and in easily controlled proportions; facilitates application of the medicament; disperses exudates of tissues and invading organisms without chemical or physical change; remains where it is applied and protects the affected area against further invasion; is non-irritating, non-drying, and is pleasing to the patient; may be easily removed, if the incorporated medicament is irritating, by flushing with sterile water or normal saline solution; is analgesic, is readily absorbed by gauze; and aids the medicament to penetrate into minute dermal crevices. The Brownian movements, which are prevalent in and characterize this true water-phase emulsion, greatly facilitate such desirable penetration and enhance the therapeutic properties of the incorporated medicament by constantly bringing particles of the medicament into contact with the seat of the affection. Since this true water-phase emulsion or medicament vehicle produces and is characterized by Brownian movements and has great wetting properties, clinical data indicate that lesser amounts of the medicament of choice are required than are now prescribed by the United States and British Pharmacopoeias for ointments. For example, 8% of sulfur suspended in this true water-phase emulsion has been found to produce results equivalent to at least 20% of sulfur in ointments of which I have knowledge.

This medicament vehicle or true water-phase

emulsion, regardless of whether it is for use alone, or for use with medicaments suspended, dispersed, or in solution therein, is composed of a mixture or solution of the following ingredients in about the critical proportions or within the critical ranges, by weight, stated: About 0.5% of a constituent or mixture of ingredients functioning as an aromatic and also as an anti-oxidant, dissolved or diluted in 60% to 65% of the base oil or "dispersed phase," consisting of a chemically pure vegetable, animal, mineral, synthesized, or equivalent oil, preferably chemically pure odorless and tasteless castor oil; a "water phase" consisting of an emulsifying agent composed of a mixture of 1% of superfatted sulfonated castor oil, and of 1% to 2% of a sulphate of one of the higher alcohols such as lauryl; of 1% to 1.25% of boric acid, 0.9% to 1% of chemically pure glycerine; and the balance distilled water. When desired or prescribed, an antiseptic may be added in the mixture, such as phenylmercuric borate 1:15,000, or others as prescribed. The mixture of the anti-oxidant and oil constituting the "dispersed phase," and the "water phase" are then intermixed and processed, as hereinafter described. These percentages are critical percentage ratios of the respective constituents to the completed vehicle of true water-phase emulsion considered as 100%.

A mixture that functions satisfactorily as an anti-oxidant, as a pleasing aromatic, and as a stabilizer to prevent deterioration of the vehicle or water-phase emulsion for long periods of time, is composed of the following ingredients in about the proportions by measure stated:

	Parts
Anisic aldehyde	10
Benzyl acetate FFC	30
Phenyl ethyl alcohol	100
Phenyl acet aldehyde	10
Terpineol	1
Geraniol	300
Hydroxycitronellal	50
Muskzylol artificial	10
Alpha amyl cinnamic aldehyde	50
Oil cananga	4
Oil jasmine artificial	10
Oil neroli artificial	15
Cinnamic alcohol	40
Oil lily valley artificial	20
Quinol	350

Another such suitable aromatic anti-oxidant that has been found satisfactory, as pleasingly aromatic, as a stabilizer, and as a preventive of deterioration of the vehicle for a long period of time, consists of the following ingredients in about the proportions by measure stated:

	Parts
Cinnamic alcohol	1
Anisic aldehyde	2
Musk artificial	3.5
Oil cananga	3.5
Phenyl acet aldehyde	4
Geraniol	5
Phenyl ethyl alcohol	8
Synthetic flower oil neroli	5
Jasolea #09842	14
Amyl cinnamic aldehyde	12
Terpineol	12
Hydroxy citronellal	10
Benzyl acetate	10
Synthetic flower oil lily of the valley	10
	100

In making this medicament vehicle or true water-phase emulsion, the emulsifying agent consisting of a mixture of superfatted sulfonated castor oil and a sulphate of one of the higher alcohols is mixed with the "water phase" consisting of boric acid, the glycerine, the antiseptic, and the water, in about the critical proportions by weight above stated. The order in which the said ingredients are mixed to form the said "water phase" is unimportant. The aromatic anti-oxidant is soluble in and is mixed with the base oil or "dispersed phase," consisting, preferably, of chemically pure odorless and tasteless castor oil, in about the stated proportions by weight which are critical. These two separate mixtures comprising the said "water phase" and the said "dispersed phase" solutions are then thoroughly and evenly mixed together by mechanical agitation to form a coarse emulsion. Said coarse emulsion is then passed through a colloid mill one or more times, and as many times as necessary, to produce a very fine emulsion having the appearance of a smear without apparent granulation, even when examined through a microscope of high power, such as a microscope of 1000 power. The reduction of the oil particles, and all particles, to this degree of fineness greatly increases the capability of the emulsion when topically applied alone, or when diluted and topically applied for the treatment of certain affections and injuries, or when used to incorporate and suspend subsequently added medicaments for the treatment of affections and injuries.

The fine emulsion obtained by proper colloid milling of the coarse emulsion as aforesaid has been used in a great many instances, and may be used, as a vehicle or emulsion to suspend various prescribed solid medicaments in a finely comminuted state for the treatment of many skin affections and wounds. Varying amounts of different prescribed solid medicaments ranging from 1% to 50% by weight as compared with the weight of the vehicle, have been used in the vehicle for topical application. These preparations containing the prescribed solid medicaments are clean, non-greasy, and are easy to apply. The amount of the solid medicament or suspensoid used may be varied as prescribed from the maximum that can be suspended in and by the vehicle to any lower amount most beneficial for the affections to be treated. The prescribed amount of solid medicament to be used in the vehicle for the treatment of an affection is first thoroughly diffused by agitation in the "water phase." By the term "water-phase" is meant the above described mixture consisting of the emulsifying agent (superfatted sulfonated castor oil and a sulphate of one of the higher alcohols), glycerine, antiseptic, and water, in the proportions by weight stated. Said agitation and diffusion completely wets all exposed surfaces of all particles of said solid medicament by the emulsifying agent or agents which function as a surface tension depressant on said particles. Next, the said water-phase containing the prescribed amount of solid medicament is added to and mixed with the other ingredients, consisting of the aforesaid mixture of the base oil of dispersed phase, and the aromatic anti-oxidant in the proportions stated. The mixture of the entire vehicle or water-phase emulsion and the prescribed solid medicament is then passed two or more times through a colloid mill and is processed thereby to such a degree of fineness that said solid medicament remains permanently in suspension in said vehicle or emul-

sion. This medicated vehicle or emulsion has the appearance of a smear without apparent granulation even when examined through a microscope of high power, as stated.

To obtain a more viscous finished medicated vehicle, about one pint of 400 (centipoise system) viscosity methylcellulose gel is mixed with one pound of the prescribed solid medicament and worked into a paste. Next, enough of the complete vehicle or water-phase emulsion to blend this pasty mass smoothly is added, and the smoothly blended mixture of said pasty mass and said vehicle or water-phase emulsion is stirred by a mechanical mixer or otherwise; then the balance of the aforesaid vehicle or water-phase emulsion to obtain the desired proportions in the finished product is added during further mechanical mixing. Thereafter, the entire mixture consisting of the said vehicle or water-phase emulsion, and the pasty mass, is passed through a colloid mill until the solid particles are reduced to or below the dimensions stated. That is, until said particles are reduced to dimensions such that, when viewed through a 1000 power microscope, they present an appearance of a smooth smear without apparent granulation. The methylcellulose functions to reduce the freezing point of the final product several degrees below freezing point of water, which is recognized as 32° F.

Any prescribed medicament which is not electrolytic or otherwise incompatible may be suspended or placed in solution in this medicament vehicle. Medicaments which have been satisfactorily incorporated in this vehicle include mercurous chloride or calomel, calamine, copper sulphate, sulfur, menthol, beta naphthol, pine tar, penicillin, allantoin, rotenone, dried blood products, phenol, salicyclic acid, tannic acid, ammoniated mercuric chloride, camphor, crysarobin, xeroform, certain tissue growth promoting factors, vitamins, various antiseptical dyes such as acroflavin, sulfathiazole, sulfanilamide, and other sulfa compounds, in varying quantities below prescribed maximum amounts alone, or in combination.

This vehicle or water-phase emulsion has been used for the suspension of turpentine as a medicament in prescribed amounts, ranging upwardly from 1% to 20%, or more, by weight, as compared with the weight of the vehicle. The prescribed amount of turpentine to be used as a medicament may be mixed with and diffused in the vehicle to form a new product that is very penetrating and is non-irritating. Clinical data have indicated the non-irritating character of this product even when applied by friction to the area being treated. In numerous instances, the vehicle containing turpentine within the ranges stated has been applied by massaging for the relief of inflamed or sore muscles, relief of chest colds by counter irritation, and as a lubricant and stimulant in massaging and osteopathic manipulation of the body.

It is an indispensable and unfailing characteristic of the present invention that the vehicle or fine emulsion obtained as described is a true water-phase emulsion and is substantially free from grease, so that it is dispersible with water and with watery and oily exudations and secretions. The greasy ointment bases heretofore generally used form envelopes around comminuted medicament particles and, to a major extent, prevent said medicament particles from reaching and directly contacting the seat of affection. The grease in said ointments does not wet the watery

exudations and secretions because it is immiscible therewith. Further, said ointment bases do not have nor create Brownian movements and do not bring the various medicament particles into direct contact with the affected area. The amounts of the ingredients of the vehicle may not be varied beyond or above the maximum percentages or ranges mentioned. The solid medicaments used may be varied from the minimum amount to the maximum amount thereof that can be suspended in and by the vehicle, according to the requirements of the cases and types of skin affections and injuries for which the preparation is intended as a treatment.

15 This is a continuation, in part, of my prior applications Serial No. 343,155, filed June 29, 1940, and Serial No. 415,432, filed September 17, 1941. I contemplate the foregoing and such other variations as may be within the range of equivalents 20 and within the scope of the appended claims.

I claim:

1. A true water-phase fine emulsion free from granulation and having Brownian movements, comprising by weight 60% to 65% of chemically 25 pure vegetable oil, and about 0.5% of an anti-oxidant dissolved in said oil; an emulsifying agent composed of a mixture of about 1% of superfatted sulfonated castor oil and 1% to 2% by weight of a sulphate of a higher alcohol; from 1% to 1.25% 30 of boric acid, 0.9% to 1% of chemically pure glycerine, and the balance distilled water.

2. A true water-phase fine emulsion free from granulation and having Brownian movements for applying medicaments to skin affections, consisting by weight of 60% to 65% of chemically pure vegetable oil supporting in solution about 0.5% of an anti-oxidant, 1% to 2% of a sulphate of a higher alcohol, 0.9% to 1% of glycerine, approximately 1% of a sulfonated castor oil, about 1% 40 to 1.25% of boric acid, and the balance distilled water to make 100%; and a medicament suspended in said emulsion and forming a medicated water-phase emulsion having Brownian movements and also having the appearance of a 45 smear without apparent granulation when examined with a microscope of high power.

3. A true water-phase fine emulsion free from granulation and having Brownian movements for applying medicaments to skin affections, consisting by weight of 60% to 65% of chemically pure 50 vegetable oil, about 0.5% of an aromatic anti-oxidant, about 1% to 2% of a sulphate of a higher alcohol, about 0.9% to 1% of glycerine, approximately 1% of sulfonated castor oil, about 1% 55 to 1.25% of boric acid, a minim of an antiseptic, and the balance distilled water to make 100%; mixed with the proportion, by weight, of 1% to 30% of turpentine as compared with the 100% of said other ingredients.

4. A true water-phase emulsion free from granulation and having Brownian movements for applying sulfur to skin affections, consisting by weight of about 0.5% of an anti-oxidant, 60% to 65% of chemically pure odorless and tasteless 65 castor oil, about 1% to 2% of a sulphate of a higher alcohol, 0.9% to 1% of glycerine, approximately 1% of a sulfonated castor oil, about 1% to 1.25% of boric acid, and the balance distilled water to make 100%; and sulfur suspended in said emulsion and applied thereby to the affected area of skin affection by said Brownian movements.

5. A true water-phase fine emulsion free from granulation and having Brownian movements, comprising 60% to 65% of chemically pure vege-

table oil, and about 0.5% of a stable anti-oxidant dissolved in said oil; an emulsifying agent composed of a mixture of about 1% of superfatted sulfonated castor oil, and 1% to 2% of a sulphate of a higher alcohol; from 1% to 1.25% of boric acid, from 0.9% to 1% of chemically pure glycerine, and the balance distilled water, all of said proportions being by weight and forming a complete emulsion having a weight of 100%.

6. A true water-phase fine emulsion free from 10 granulation and having Brownian movements,

comprising 60% to 65% of chemically pure oil, and about 0.5% of a stable anti-oxidant dissolved in said oil; an emulsifying agent composed of a mixture of about 1% of superfatted sulfonated castor oil, and 1% to 2% of a sulphate of a higher alcohol; from 1% to 1.25% of boric acid, from 0.9% to 1% of chemically pure glycerine, and the balance distilled water, all of said proportions being by weight and forming a complete emulsion having a weight of 100%.

MORTON B. CROWE.
